UNITED STATES PATENT OFFICE

FRED A. WEIDHAAS, OF EASTHAMPTON, MASSACHUSETTS, ASSIGNOR TO UNITED ELASTIC CORPORATION, OF EASTHAMPTON, MASSACHUSETTS, A CORPORATION OF MASSACHUSETTS

WEBBING

Application filed November 24, 1931. Serial No. 577,073.

The present invention relates to woven elastic webbing and more particularly to the novel weave thereof.

Among the objects of the invention are 5 the production of a loop edge providing a lace effect along the edge of the fabric which however is not necessarily confined to any particular weave of fabric, but may be used on any elastic fabric.

10 Another object is to provide in such a weave an arrangement in which the lace or loop threads lay straight during the process of weaving, but in which, as the web contracts in the process of weaving the 15 fabric, the loop or lace effect will be produced, due to the novel manner of attaching the lace threads to the body of the web.

This effect may be increased or decreased 20 as desired, by shortening or lengthening the distance between the points of attachment 25 of the lace threads to the body.

Another object is to provide a loop or lace edge so connected to the main woven fabric as to prevent unravelling or detachment therefrom.

Still another object is to form an edge, having the appearance of a crocheted edge, but which is woven into the fabric during the weaving of the body of the fabric.

30 The invention further contemplates provision of a novel weave in the body of the fabric.

Various novel and ornamental effects may be produced by using lace threads of desired colors or by using lace threads of a color contrasting to that of the main weave.

To the attainment of the above, and other objects which will appear as the description proceeds, reference may be made to 40 the accompanying drawings, in which

Fig. 1 is an enlarged face view of a fabric embodying the invention, with the web extended and the weft thread laid in without tension; and

45 Fig. 2 is a similar view showing the lace

effect as it appears in actual operation on the loom.

Referring more specifically to the drawings, wherein like reference numerals designate like parts, Figure 1 illustrates a web 50 or fabric having a filling or weft 10, a series of rubber warps 12, interspersed with binder warps 14 and center warps 16. 18 designates the edge wires. A series of loop or lace forming threads 20, 21 and 22, preferably three in a row, are laid in along each edge or selvage of the fabric.

As the weft 10 passes back and forth transversely of the web, return loops 24 and 26 will be formed, and the innermost lace 60 thread 20 is laid in to pass over the pair of wefts forming loop 24, and under the adjacent pair, forming loop 26. The intermediate thread 21 passes under the loop 24 and over the loop 26, while the outer thread 65 22 passes through both of the loops 24 and 26. In Fig. 1 the weft 10 is illustrated as laid in without tension to illustrate as fully as possible the manner in which the lace and weft threads are interlaced and showing 70 how they are placed in relation to each other in this particular weave.

In Figure 2 the fabric and lace effect is illustrated as it appears while being woven, the elastic web being under weaving tension 75 on the loom, the weft thread being under regular shuttle tension and the outside lace thread being pulled into the selvage or edge of the web. This outside thread 22 will have been pulled through, and not around 80 the other two lace threads 20 and 21, and the two inside lace threads 20 and 21 will have crossed by operation of the harness through which they are drawn, and hence will be bound by the pulling in of the outside lace 85 thread 22 as drawn to the edge wire 18 by the filling or weft thread.

It will be observed by reference to the drawings that the filling or weft thread is carried over and under the warps in a novel 90

manner to produce a highly ornamental and satisfactory webbing, in addition to the lace effect produced in the manner hereinbefore set forth and described.

5 Having thus described my invention, what I claim as new and desire to secure by Letters Patent of the United States, is:—

10 1. The method of weaving a lace edge on a fabric incorporating elastic warps, which comprises laying a warp thread over and under adjacent pairs of wefts respectively, at spaced intervals, laying a second warp thread under and over said pairs of wefts respectively, laying a third warp thread 15 through the end loops formed by said adjacent pairs of weft threads, said wefts under normal tension being effective to draw in said warp threads and bind them at spaced intervals into the selvage of the 20 fabric.

25 2. The method of weaving a fabric incorporating elastic warps, which comprises forming pairs of weft loops by weft returns at spaced intervals along the fabric, of slightly greater length than an intermediate weft, laying a lace forming thread over one loop of each pair and under the adjacent loop, laying a second lace forming 30 thread under said first mentioned loop of each pair and over the second loop, laying a third lace forming thread through both of the loops of each pair, said loops, under normal tension, being effective to draw in said lace forming threads and bind them at 35 spaced intervals into the fabric.

40 3. In combination with a fabric comprising elastic warp threads and weft threads forming loops, spaced apart by intermediate wefts, at the selvage of the fabric, a plurality of lace forming threads extending along the selvage of the fabric, one of said latter threads being passed over a weft loop and under an adjacent weft loop, another of said threads being passed under said first 45 weft loop and over said adjacent weft loop and a third of said lace threads passing through the weft loops and effective to bind said first two lace threads at spaced intervals into the selvage of the fabric as the weft thread is placed under regular tension.

50 4. A woven fabric embodying an elastic warp and a weft arranged to form loops at the selvage of the fabric and having an ornamental edge formed of a plurality of warp threads, the inner two of said warp threads being woven over and under the weft loops and a third warp thread being bound into the selvage by spaced weft loops and in turn binding said first mentioned 55 threads in the fabric.

55 5. A fabric comprising elastic warp threads, and weft threads forming loops, spaced apart by intermediate wefts at the 60 edge of the fabric, a plurality of lace forming threads extending along the edge of the

fabric, one of said latter threads being passed over a weft loop and under an adjacent weft loop, another of said threads being passed under said first weft loop and over said adjacent weft loop and crossing said first lace thread, and a third of said lace threads passing through both weft loops outside of said first threads, and effective to bind said crossed lace threads at spaced intervals into the fabric as the weft threads are placed under regular tension. 70

6. A woven fabric embodying an elastic warp and a weft extending back and forth to provide return loops and having at one edge an ornamental lace effect formed of a plurality of threads, the inner two of said lace threads being woven over and under the weft and the third thread being bound into the fabric by spaced weft loops and in turn binding said first mentioned lace 75 threads into the fabric. 80

7. In a woven elastic fabric, an ornamental lace effect along an edge of the fabric formed by warp threads extending along said edge, an outer one of which is secured in cross engaging relation to adjacent warp threads by wefts, to the edge at intervals spaced apart by at least one weft, and effective to secure the remainder of said threads to the fabric, thereby to provide 90 lace forming loops when the fabric is under normal contraction. 95

8. A woven elastic fabric embodying a warp and a weft and having at an edge an ornamental lace effect formed by warp threads, an outer one of which is secured in cross engaging relation to adjacent warp threads by wefts, to the selvage at intervals spaced apart by at least one weft, and effective to secure the remainder of said threads 100 to the fabric thereby to form warp loops when the fabric is under normal contraction. 105

9. A woven elastic fabric embodying a warp, and a weft extending back and forth to provide return loops, and having at an edge an ornamental lace effect formed by warp threads, an outer one of which is secured in cross engaging relation to adjacent warp threads by wefts, to the selvage 110 by weft loops at spaced intervals separated by intermediate wefts and effective to secure the remainder of said warp threads to the fabric, thereby to form warp loops when the fabric is under normal contraction. 115

10. The method of weaving an elastic fabric which comprises forming weft loops along an edge of the fabric and securing warp threads in cross engaging relation to each other along said edge into the selvage 120 of the fabric at intervals by weft loops spaced apart at least one weft while said fabric is under tension, and releasing said fabric from tension, thereby forming an ornamental edge consisting of warp loops. 125

11. The method of weaving an elastic 130

fabric which comprises forming weft loops along an edge of the fabric, laying warp threads over and under weft loops spaced apart by intermediate wefts while said fabric is under tension, and securing said warp threads at said spaced loops by laying an additional warp thread through said loops and releasing said fabric from tension, thereby forming an ornamental edge 10 consisting of warp loops.

In testimony whereof I affix my signature.
